(57) **CLAIM**

The ornamental design for a lap diner, as shown and described.

DESCRIPTION

FIG. 1 is a perspective exploded view of an embodiment of the lap diner with a round dinner platter and a rectangular pillow.

FIG. 2 is a top down view of the lap diner with the dinner platter detached from the pillow.

FIG. 3 is a top down view of the lap diner with the dinner platter detached from the pillow

FIG. 4 is a side view of the lap diner with the dinner platter detached from the pillow

FIG. 5 is another side view of the lap diner with the dinner platter detached from the pillow

FIG. 6 is a front view of the lap diner with the dinner platter detached from the pillow

FIG. 7 is another view of the lap diner with the dinner platter detached from the pillow

FIG. 8 is a perspective view of the lap diner with the dinner platter attached to the pillow.

FIG. 9 is a perspective exploded view of another embodiment of the lap diner with a rectangular dinner platter and a rectangular pillow.

FIG. 10 is a top down view of the lap diner with the dinner platter detached from the pillow.

FIG. 11 is a top down view of the lap diner with the dinner platter detached from the pillow

FIG. 12 is a side view of the lap diner with the dinner platter detached from the pillow

FIG. 13 is another side view of the lap diner with the dinner platter detached from the pillow

FIG. 14 is a front view of the lap diner with the dinner platter detached from the pillow

FIG. 15 is another view of the lap diner with the dinner platter detached from the pillow

FIG. 16 is a perspective view of the lap diner with the dinner platter attached to the pillow.

FIG. 17 is a perspective exploded view of another embodiment of the lap diner with a round dinner platter and a round pillow.

FIG. 18 is a top down view of the lap diner with the dinner platter detached from the pillow.

FIG. 19 is a top down view of the lap diner with the dinner platter detached from the pillow

FIG. 20 is a side view of the lap diner with the dinner platter detached from the pillow

FIG. 21 is another side view of the lap diner with the dinner platter detached from the pillow

(Continued)

FIG. 22 is a front view of the lap diner with the dinner platter detached from the pillow

FIG. 23 is another view of the lap diner with the dinner platter detached from the pillow

FIG. 24 is a perspective view of the lap diner with the dinner platter attached to the pillow.

FIG. 25 is a perspective exploded view of another embodiment of the lap diner with a rectangular dinner platter and a round pillow.

FIG. 26 is a top down view of the lap diner with the dinner platter detached from the pillow.

FIG. 27 is a top down view of the lap diner with the dinner platter detached from the pillow

FIG. 28 is a side view of the lap diner with the dinner platter detached from the pillow

FIG. 29 is another side view of the lap diner with the dinner platter detached from the pillow

FIG. 30 is a front view of the lap diner with the dinner platter detached from the pillow

FIG. 31 is another view of the lap diner with the dinner platter detached from the pillow

FIG. 32 is a perspective view of the lap diner with the dinner platter attached to the pillow; and,

FIG. 33 is an exploded perspective view of a lap diner.

Broken lines are for illustrative purposes, and do not form part of the claimed design.
